(57) **CLAIM**

The ornamental design for a guitar body, as shown and described.

DESCRIPTION

FIG. 1 is a front perspective view of a guitar body showing our new design;

FIG. 2 is a front elevational view of the guitar body;

FIG. 3 is a rear elevational view of the guitar body;

FIG. 4 is a top plan view of the guitar body;

FIG. 5 is a bottom plan view of the guitar body;

FIG. 6 is a right side elevational view of the guitar body; and,
FIG. 7 is a left side elevational view of the guitar body.

The broken lines of the drawing are for illustrative purposes only and form no part of the claimed design.
